UNITED STATES PATENT OFFICE.

WILLIAM H. CRANE, OF POUGHKEEPSIE, NEW YORK, ASSIGNOR TO MOLINE PLOW COMPANY, A CORPORATION OF ILLINOIS.

FOLDING DIVIDER FOR HARVESTERS.

1,302,768.

Specification of Letters Patent.

Patented May 6, 1919.

Application filed May 6, 1916. Serial No. 95,779.

To all whom it may concern:

Be it known that I, WILLIAM H. CRANE, a citizen of the United States, residing at Poughkeepsie, in the county of Dutchess 5 and State of New York, have invented certain new and useful Improvements in Folding Dividers for Harvesters, of which the following is a specification, reference being had therein to the accompanying drawing.

10 My invention relates to grain dividers for harvesters and has reference more particularly to that type of divider which is adapted to be folded rearwardly to reduce the width of the machine for transportation or 15 storage, the object of the invention being to provide a construction of simple, efficient and durable form which will retain the divider rigidly and firmly and give it great strength when it is in its lowered 20 active position, but will permit the same to be conveniently and readily moved to an inoperative folded position.

With this end in view my invention consists in combining with a divider and a supporting member pivotally connected with the divider and machine frame and adapted to swing upwardly in folding the divider, a bracing member pivoted respectively to the frame and divider so as to swing upwardly 30 with the supporting member and disposed above the supporting member in position to brace the divider against end thrusts and strains when it is down in operative position.

35 The invention consists also in certain novel details of construction and form of the apparatus designed to prevent the divider from being accidentally swung upward to folded position in the event of the 40 same encountering obstructions in the field, which features will be more particularly described later on.

I have in the accompanying drawings illustrated my invention in the particular 45 detailed form and construction which I prefer to adopt and which in practice has been found to answer to a satisfactory degree the ends to be attained. It will be manifest, however, that these details may be variously 50 changed and modified without departing from the limits of my invention; and it will be understood that the invention is not limited to any particular form or construc-

tion of the parts except in so far as such limitations are specified in the claims. 55

In the accompanying drawings:

Figure 1 is a side elevation of the forward portion of a harvester as viewed from the grain side, the folding divider being shown down in active position, and the grain wheel 60 being indicated by dotted lines.

Fig. 2 is a similar view showing the divider swung back to a folded position.

Fig. 3 is a top plan view of the parts shown in Fig. 1, portions being broken away 65 and other parts being shown in section to better illustrate the construction.

Fig. 4 is a fragmentary view, on an enlarged scale, of the rear end of the thrust link and the adjacent portion of the frame 70 to which the link is pivoted, the link being shown extended in the position it occupies when the divider is down in action.

Fig. 5 is a similar view, partly in section, showing the thrust link in the position it 75 occupies when the divider is swung rearwardly to folded position, and the stop on the frame which limits the rearward movement of the link.

Fig. 6 is a horizontal sectional plan view 80 on enlarged scale taken on the line $a-a$ of Fig. 1.

Referring to the drawings:

1 indicates the forward portion of the grain side of the frame of the machine and 85 including the usual grain receiving platform 2, and the grain wheel guide 3, a wheel slide 4 being mounted in said guide and adjustable vertically therein as usual, and a grain wheel 5 being mounted on the slide. 6 indicates a grain divider consisting of the divider board 6^a and the shield 6^b depending 90 therefrom, which divider, when in active operative position, extends in a fore and aft direction at the grain end of the platform and projects forwardly therefrom. 95

The forward end of the divider is connected with the frame by means of a supporting member 7 consisting of two links 7^a jointed at their rear ends to the frame by 100 means of horizontal transverse pivot bolts 7^b, and converging thence forwardly and jointed at their forward ends to the divider point by means of a horizontal transverse pivot 8, the construction being such that by 105 swinging the supporting member upwardly

on its pivotal connection with the frame, the divider will be swung upwardly and rearwardly in a curved path to a folded position as shown in Fig. 2, the said member when 5 the divider is swung down to active position extending forwardly at a slight upward inclination from the horizontal as shown in Fig. 1. 9 indicates a standard which is firmly and fixedly bolted at its upper end to 10 the divider board and terminates at its lower end in a depending projection 9^a and which, when the divider is down in action, will extend in a vertical position, this standard being preferably in the form of an angle bar 15 as shown in section in Fig. 3. When the divider is in lowered active position the lower end of the standard seats in a socket 10 in a socket member 10^a on the frame, and it is firmly clamped and held therein by 20 means of a clamping bolt 11 screwed through a bracket 12 on the socket member with its inner end in position to engage in the angle of the standard as shown in Fig. 3.

Disposed above the supporting member 7 25 and pivoted at its forward end to the standard at or about midway between the ends of the latter as at 14^a, is a bracing member 13 in the form of a link, the rear end of which is pivoted by means of a horizontal pivot 30 bolt 14 to an ear 15 projecting forwardly from the frame member or wheel guide 3. When the divider is down in action, this link extends in a horizontal position and it acts in connection with the rigid standard 35 9 to brace and strengthen the divider against end thrusts and strains acting rearwardly in the advance of the machine through the field, such strains being exerted endwise on the bracing member by reason of the horizontal position of the latter. At the same 40 time in the folding action of the divider, the bracing member will swing upwardly with the supporting member and will constitute in connection with said member, a parallel motion causing the divider to swing upwardly and rearwardly in a curved path. The walls of the socket 10 in which the 45 depending projection on the standard 9 seats, are straight and they intersect the path of movement of said projection when it leaves the socket in the folding action of the divider, which will cause the projection to bind in the socket. This binding action may be readily overcome if the 50 lifting force to fold the divider is applied to the standard 9 or adjacent thereto, but if said force is applied to the outer end of the divider, the binding of the standard in the socket becomes more pronounced by 55 60 reason of the natural spring and bending of the parts, the result being that the divider will not be liable to accidental folding when its forward end encounters obstructions in the field.

65 When the divider is thus swung back to

folded position, it is limited in its rearward motion by means of a stop 16 on the frame member 3, adjacent the pivotal connection of the thrust link therewith, this stop being in position to be engaged by the link when the latter is swung back, and will act to support the same in this position.

The relation of the parts is such that when the divider is swung back to folded position, the supporting member will extend at a rearward inclination from the vertical, and the weight of the divider will act to hold the same in its folded position, with the bracing link bearing at its lower end against the stop 16.

When the divider is to be folded, the clamping bolt 11 is first released, and by applying a lifting force on the standard 9 or on the parts adjacent said standard, the binding of the projection in the socket will 85 be overcome, and the divider may be readily swung upwardly and rearwardly to folded position.

Having thus described my invention, what I claim is:

1. In a harvester, the combination of a machine frame including a receiving platform, a divider projecting beyond the platform, a supporting member hinged at its forward end to the divider and at its rear end to the frame to permit the divider to be folded upwardly and rearwardly, and a bracing member hinged at its forward end to the divider and at its rear end to the frame and extending substantially parallel with the supporting member when the divider is in lowered operative position.

2. In a harvester, the combination of a frame including a receiving platform, a divider projecting beyond the platform, a supporting member hinged at its forward end to the divider and at its rear end to the frame to permit the divider to be folded upwardly and rearwardly, and a bracing member arranged above the supporting member and hinged at its forward end to the divider and at its rear end to the frame and extending substantially parallel with the supporting member when the divider is in lowered operative position.

3. In a harvester, the combination of a frame including a receiving platform, a divider projecting beyond the platform, a supporting member hinged at its forward end to the divider and at its rear end to the frame to permit the divider to be folded upwardly and rearwardly, and a horizontal bracing link hinged at its forward end to the divider and at its rear end to the frame.

4. In a harvester, the combination of a frame including a receiving platform, a divider projecting beyond the platform, a supporting member hinged at its forward end to the divider and at its rear end to the frame to permit the divider to be folded

upwardly and rearwardly, and a horizontal bracing link arranged above and in rear of the radius member, said link having its forward end hinged to the divider and its rear 5 end jointed to the frame.

5. In a harvester, the combination of a frame including a receiving platform, a divider projecting beyond the platform, a supporting member hinged at its rear end 10 to the frame and at its forward end to the divider, an upright standard fixed to the divider, and a horizontal bracing link hinged at its forward end to the standard and at its rear end to the frame.

15. 6. In a harvester, the combination of a frame including a receiving platform, a divider projecting forwardly therefrom and movable upwardly and rearwardly, an upright standard fixed to the divider, a bracing link pivoted to the standard and frame 20 respectively, and a socket on the frame to receive the lower end of the standard when the divider is swung down in action.

25. 7. In a harvester, the combination of a frame including a receiving platform, a divider projecting beyond the platform and movable upwardly and rearwardly, a supporting member connected respectively with the divider and machine frame and adapted 30 to swing upwardly with the divider, a bracing link pivoted to the divider and frame respectively and movable rearwardly with the divider when the latter is swung rearwardly, and a stop on the frame adjacent 35 the pivotal connection of the link therewith and in position to be engaged by said link.

and limit the rearward movement of the same.

8. In a harvester, the combination of a frame including a receiving platform, a divider projecting beyond the platform, a supporting member jointed at its forward end to the divider and at its rear end to the frame and adapted to be swung rearwardly to fold the divider, jointed connections between the divider and frame to support the divider in rear of the support afforded by the supporting member, and a stop to limit the rearward movement of the divider and sustain the same in folded position, said 50 parts being of such form and relative disposition that when the divider is supported in folded position, the supporting member will extend at a rearward inclination from the vertical and the weight of the divider 55 will hold the same in its folded position.

9. In a harvester, the combination of a frame provided with a socket having straight walls, a divider connected to said frame to swing upwardly in a curved path, and provided with a fixed projection adapted when the divider is down in operative position, to seat in said socket, whereby when the divider is swung upwardly the projection will bind 60 in the socket and will tend to resist the folding action.

In testimony whereof, I have affixed my signature in presence of two witnesses.

WILLIAM H. CRANE.
